UNITED STATES PATENT OFFICE.

EDWARD E. LAWRENCE, OF JAMAICA, NEW YORK, ASSIGNOR TO LOOSE WILES BISCUIT COMPANY, OF LONG ISLAND CITY, NEW YORK, A CORPORATION OF NEW YORK.

WAFER OR BISCUIT SANDWICH-MAKING MECHANISM.

Application filed August 4, 1919. Serial No. 315,171.

To all whom it may concern:

Be it known that I, EDWARD E. LAWRENCE, a citizen of the United States, and a resident of Jamaica, in the county of Queens 5 and State of New York, have invented an Improvement in Wafer or Biscuit Sandwich-Making Mechanism, of which the following description, in connection with the accompanying drawings, is a specification, 10 like characters on the drawings representing like parts.

This invention relates to wafer or biscuit sandwich-making mechanism.

In order that the principle of the invention 15 may be readily understood, I have disclosed a single embodiment thereof in the accompanying drawings, wherein—

Fig. 1 is a side elevation of one form of mechanism embodying my invention;

20 Fig. 2 is a plan view of the mechanism shown in Fig. 1;

Fig. 3 is a cross sectional view upon the line 3—3 of Fig. 2;

25 Fig. 4 is a perspective detail of a slightly modified form of a portion of the mechanism;

Fig. 5 is a front elevation of the stacker preferably used as a part of the mechanism of my invention;

30 Fig. 6 is a plan view of said stacker and of the means for discharging wafers, biscuits or the like therefrom;

Fig. 7 is a vertical section upon the line 7—7 of Fig. 5, and showing also a hand 35 device for inserting wafers or the like in said stacker; and

Fig. 8 is a detail of a portion of said hand device.

While the mechanism of my invention is 40 adapted for use in various relations, it is more particularly adapted to be employed upon or in connection with machines for depositing coating material upon food products, and more particularly for depositing jelly, icing or a sweetened material upon cakes, biscuits or wafers.

While the mechanism of my invention 45 may be employed in connection with any suitable means for depositing such material upon cakes, crackers or the like, I pref-

erably employ mechanism substantially like or similar to that disclosed in the patent to Edward Legler, No. 1,260,553, March 26, 1918, wherein is disclosed means for depositing jelly, upon which jelly a small quantity 55 of marshmallow is thereafter deposited. Obviously any suitable substance may be deposited upon the cakes or crackers and herein I have indicated generally means for depositing a single substance upon each cake, 60 cracker, wafer or the like.

In the said Legler patent means are disclosed for pushing cakes or like products from a hopper or receptacle onto a traveling belt. Such means are preferably employed in connection with or as a part of the mechanism herein disclosed, but I have not illustrated herein such means, since the cakes or other products may be deposited in any suitable manner upon the apron or other 70 conveyer.

While any suitable conveyer may be employed, I preferably provide a belt or apron 1 which is supported upon a suitable framing, certain of the uprights of which are 75 represented at 2—2. Preferably the apron, which is endless, is of very considerable length, and the cakes or other products carried thereby and treated while thereon are discharged therefrom in a manner not herein 80 represented.

The cakes or the like having been suitably deposited or positioned upon the belt 1, which is preferably intermittently driven as described in the said Legler patent, are preferably by a pusher, as shown in said patent, moved under a suitable hopper or receptacle 3 containing the jelly, icing or other filling, as more fully disclosed in said Legler patent. The material is discharged from the said 90 hopper or receptacle 3 by suitable valve means, preferably of the type shown in the said patent, and the cakes having the material so deposited thereon are, in the onward movement of the belt 1, brought with 95 in the range of movement of a second feeding device, herein represented as a pusher 4 and preferably similar to that shown in the said Legler patent. As herein indicated most clearly in Fig. 2, the pusher 4 has a 100

forward serrated edge and is connected at its ends to longitudinally extending rods or bars 5, which at their opposite ends are connected to the uprights 6 of two longitudinally extending slides 7, which at their opposite ends are pivotally connected at 8 to links 9 themselves pivotally connected at 10 to two levers 11 mounted upon the shaft 12 for rocking movement. In a manner not herein illustrated, but which preferably is substantially the same as that disclosed in the said Léglér patent, the shaft 12 is rocked so as to impart a movement of reciprocation to the pusher. 10
15 In order that the pusher 4 shall not interfere with the onward moving biscuits or the like, I provide means which may be similar to that shown in the said Léglér patent for imparting movement in a generally rectangular path to the said pusher. For that purpose I have herein shown opposite guide members 13 having trackways with pivoted parts 14, 15, so that upon the movement of the pusher 4 to the left viewing Fig. 1, the forward parts of the rods or bars 5 are guided beneath the pivoted members 14, and upon their return are guided thereabove and over the pivoted part 15, depressing the latter, which immediately is returned by suitable springs into the position indicated in Fig. 1. Upon the next movement of the rods or bars 5 to the left, viewing Fig. 1, they are suitably guided beneath the pivoted members 15. In this or any other suitable manner, the cakes or the like are intermittently fed forward and are by the intermittently moving apron 1 brought into suitable position to have superimposed thereon another cake or the like, 30 so that what may be termed a sandwich or filled wafer is formed or provided, the same being composed of two cakes or the like between which is a suitable filling that has been deposited from the hopper or receptacle 3. While the superposed cakes may be positioned upon the apron-carried cakes 16 having the filling material 17 deposited thereon, preferably I provide means wherein a relatively large number of cakes or 40 the like 18 may be deposited to be automatically released intermittently as the apron-carried cakes 16 are brought thereunder.

For this purpose, I have herein represented a hopper or stacking member generally indicated at 19 and which is of sufficient width to extend across the apron 1. At suitable intervals it is provided with upright partitions 20 spaced a distance apart substantially corresponding to the diameter of the cakes. From said partitions preferably extend flanges 21—21 preferably tapered at their upper ends as indicated at 22. The adjacent edges 23 of said flanges are spaced sufficiently apart to permit the operator to place the cakes or the like in piles

in the hopper between the partitions 20. While the cakes may be deposited by hand singly or in piles between the partitions 20, I preferably provide a tool or holder by which a series of cakes may be taken from the mass or group and readily deposited in the hopper. For this purpose I have, in Figs. 7 and 8, represented a holder 24 herein shown as composed of a single piece of spring metal bent to form a handle 25 and parallel spaced ends 26—26 between which the cakes are received. It is desirable that a pile or series of the cakes be grasped firmly by the tool 24, but in such a manner that the cakes will not be crushed by reason of the operative applying too great pressure to the tool. For that purpose I preferably provide suitable stop means herein represented as a bolt 27 secured at its end 28 to one part of the tool and extending at its other end 29 through an opening 30 in the tool. The bolt 27 is threaded as indicated at 31 for the reception of nuts 32 which may be moved to any position upon the bolt. The construction is such that having set the nuts 32 at the desired point, the tool is manipulated to grasp a set or pile of the cakes and the spaced ends 26 of the tool are moved toward each other by the pressure of the operative's hand until the wall or part of the tool having the opening 30 therein takes against the nut 32. This permits the pile of cakes to be grasped firmly and yet prevents over pressure and crushing thereof.

In order to deposit the pile or set of cakes held by the tool 25 in one of the compartments of the hopper 19, the filled tool is held directly above one of the compartments with the handle portion 25 extending at right angles to the transverse wall of the compartment. The tool is then lowered so as to move the held cakes downward into the compartment, the spaced ends 26 of the tool entering the compartment between the edges 23 of the flanges 22. After the tool has been lowered sufficiently to bring the held set of cakes down substantially to those previously positioned in the hopper, the tool 25 is withdrawn by a movement at right angles to the transverse wall of the hopper 19.

Obviously, however, any other suitable means may be employed to position the cakes in the hopper or stack member 19.

The hopper 19 is supported in any suitable manner slightly above the normal position or general level of the apron 1, as indicated in Fig. 7. Any suitable means may be employed to support the hopper in the said position.

The apron 1 is adapted to be elevated at a point directly beneath the hopper 19, so as to lift a transverse row of the cakes 16 with the superposed filling 17 up against

the lowermost and released cracker in each compartment of the hopper 19. For this purpose, I have represented the side members 33, 33 of the framing as having secured thereto suitable angle irons 34 wherein are guided for vertical movement rods 35 which at their upper ends are connected to brackets 36 themselves connected to spaced channel irons 37 extending transversely of the 10 apron 1 and adapted to elevate the portion of the apron contacting therewith, so as to lift the cakes 16 with their deposited filling 17 into engagement with the lowermost cakes 38 in the several compartments 15 of the hopper 19.

Instead of employing the spaced channel irons 37, I may, as shown in Fig. 4, secure to the top of the brackets 36 a plate or strip 39 of a length corresponding to the width of 20 the apron and of a sufficient width to provide for the elevation of a sufficient zone or section of the apron 1. It is important that but a single cake is released at a time from each compartment of the hopper 19. While 25 for this purpose any suitable means, such as an escapement or other device, may be provided, I have herein represented the hopper 19 as provided at its lower end with transverse bars 40, shown most clearly in Fig. 7 30 and adapted to receive, for sliding movement in the opposite ends thereof, a pair of rods 41 upon the outer ends of which are suitably supported transverse bars 42, wherein are secured, as by means of bolts 43, a series of escapement pins 44, 45. Said bars 42 together with the rods 41 thus form a sliding frame supporting said escapement pins 44, 45. Said pins, as clearly shown in Fig. 7, are arranged in two sets spaced vertically a distance equalling the thickness of a single cake and also having their ends so placed with respect to each other that when the pins 44 are moved into and through the hopper 19,—that is, to the left viewing Fig. 45 7,—they pass between the two lowermost cakes in each compartment, and as they enter therebetween the pins 45 are at the same time withdrawn from beneath the lowermost cake in each compartment. This permits the 50 lowermost cake to drop from each compartment, the cake immediately above what was the lowermost cake being now held up and resting upon the pins 44. I provide suitable means whereby a zone or section of the apron 55 1 is elevated together with a transverse row of the cakes 16 at substantially the same time that a transverse row of the cakes is released from the compartments of the hopper 19, whereby the apron-supported cakes 16 with their filling 17 are lifted into engagement with a released row of cakes, the lifting movement of the apron being relied upon to force the elevated row 16 of the cakes 60 against the released row of cakes 38 with sufficient force to reduce to a thin sheet the

filling material 17, the pins 45 acting as an abutment for the released cakes 38 as indicated most clearly in Fig. 3.

While for this purpose any suitable means may be provided, I have herein represented 70 a lever 46 pivoted at 47 upon a bracket 48 and having a roll 49 adapted to be acted upon by a suitable cam 50 mounted upon a shaft 51. The roll 49 is held in engagement with the cam 50 by means of a suitable coil spring 75 52. To the opposite end of the lever 46 is pivoted at 53 a link 54, the upper end whereof is received in a slot 55 in the arm 56 of a bell crank lever 57 pivoted at 58 in the framing of the machine. The opposite arm 59 80 of said lever has pivotally secured to its upper end at 60 a link 61 connected at its outer end to one of the rods 41 of the escapement mechanism.

Fast with the lever 57 are a pair of lever 85 arms 62 at opposite sides of the machine and adapted at their outer ends to take under the ends of the rods 35 by which a zone or section of the apron 1 is intermittently lifted. The construction and arrangement of parts 90 are such that as a zone or section of the apron 1 with its superposed row of cakes 16 is elevated, the escapement pins 45 are moved to the right, viewing Fig. 7, immediately following the release of the bottom-most cakes in the several compartments of 95 the hopper 19. The said released cakes are received upon the filling 17 of the apron-supported cakes 16 and the pins 45 are immediately brought into position to act as an 100 abutment or backing for the said cakes 38, so that the lifting movement of the apron causes the filling 17 to be reduced to a thin layer which adheres to each pair of cakes 16, 38, thus forming them into what may be 105 termed a sandwich or filled wafer. Thereupon the elevated section of the apron is lowered and the onward movement of the apron carries the formed row of sandwiches or filled wafers from beneath the hopper 19 110 and brings another row of the cakes 16 with the overlying mass of filling 17 into position beneath the hopper. Thereupon the described cycle of operations is repeated.

Having thus described one illustrative embodiment of my invention, I desire it to be understood that although specific terms are employed, they are used in a generic and descriptive sense and not for purposes of limitation, the scope of the invention being set 115 forth in the following claims.

Claims:

1. Wafer or biscuit sandwich-making mechanism comprising in combination, a travelling support for a lower cake, cracker or the like, means to support in superposed relation upper cakes, crackers or the like, releasing means for an upper cake to permit the superposition thereof upon a lower cake, and means to bring the upper and lower 125 130

4
cakes with an interposed filling into engaging relation with each other against said releasing means as an abutment.

2. Wafer or biscuit sandwich-making mechanism comprising in combination, a travelling support for a lower cake, cracker or the like, means to support in superposed relation upper cakes, crackers or the like, a combined releasing means and abutment for the upper cakes, and means to elevate the lower cake into engaging relation with the released upper cake against said combined releasing means and abutment.

3. Wafer or biscuit sandwich-making mechanism comprising in combination, a travelling support for a lower cake, cracker or the like, means to support in superposed relation upper cakes, crackers or the like, releasing means for the upper cake having a to and fro movement and having a part adapted to serve as an abutment following release of an upper cake, and means co-acting with the abutment to press an upper and lower cake into engaging relation with an interposed filling.

4. Wafer or biscuit sandwich-making mechanism comprising in combination, a travelling apron to support a series of lower cakes, crackers or the like, a hopper to support in superposed relation a series of upper cakes, a combined releasing means and abutment for effecting the release of the lowermost upper cakes, and means to lift a transverse zone or section of the apron with lower cakes thereon against the combined releasing means and abutment.

5. Wafer or biscuit sandwich-making mechanism comprising in combination, conveyor means to support a lower cake, cracker or the like, a hopper having means to support a superposed series of upper cakes, crackers or the like, and a releasing means for the lowermost cracker comprising a horizontally movable frame carrying upper and lower members offset from each other to permit the release of individual cakes and the retention of the remaining superposed cakes.

6. Wafer or biscuit sandwich-making mechanism comprising in combination, conveyor means to support a lower cake, cracker or the like, a hopper having means to support a plurality of superposed series of upper cakes, crackers or the like, and a releasing means for the upper cakes comprising a pair of opposed vertically spaced and relatively fixed rows of pin-like members alternately reciprocable across the base of the hopper to permit the discharge of a single cake of each series.

60 7. Wafer or biscuit sandwich-making mechanism comprising in combination, means to support a lower cake, cracker or the like, a hopper having means to support a superposed series of upper cakes, crackers or the like, reciprocable releasing means for

the lowermost cake, and means acting substantially simultaneously to lift the support for the lowermost cake and to reciprocate said releasing means.

8. Wafer or biscuit sandwich-making mechanism comprising in combination, a travelling belt or apron for a series of lower cakes, means to support in superposed relation a series of upper cakes, means to supply a filling to the lower cakes, combined upper cake-releasing and abutment means, and operating means therefor, whereby the lowermost upper cake is released and the apron with a lower cake is pressed against said upper cake and the latter is thereby pressed against said releasing means as an abutment.

9. Wafer or biscuit sandwich-making mechanism comprising in combination, a travelling apron for a series of lower cakes, a support for superposed upper cakes, releasing means for said cakes comprising pins 44, 45, lifting means for said belt located below the superposed upper cakes, a lever 57, means to operate said lever, and connections from said lever to said lifting means and to said releasing means.

10. Wafer or biscuit sandwich making mechanism comprising in combination, travelling means for a series of lower cakes, a support for superposed upper cakes, releasing means for said cakes comprising pins 44, 45, lifting means for said belt located below the superposed upper cakes, a lever 57, connections therefrom to said lifting means and also to said releasing means, and means to operate said lever 57 during periods of rest of said traveling means.

11. Wafer or biscuit sandwich-making mechanism comprising in combination, travelling means to feed lower cakes, crackers or the like, a hopper having means to support a superposed series of upper cakes, crackers or the like, releasing means for the lowermost unit of said series comprising a frame horizontally movable at the mouth of said hopper and supporting at opposite sides thereof sets of vertically spaced pins, and means to reciprocate said releasing means to effect the discharge of a single upper cake.

115 12. Wafer or biscuit sandwich-making mechanism comprising, in combination, means to support a lower cake, cracker or the like, a hopper having means to support a superposed series of upper cakes, crackers or the like, reciprocable releasing means for the upper cakes comprising a frame 41, 42, 41, 42 and vertically and laterally spaced sets of pins 44, 45 removably mounted therein and means for positively reciprocating said frame.

13. Wafer or biscuit sandwich-making mechanism comprising in combination, means to support a lower cake, cracker or the like, a hopper having means to position

a superimposed series of upper cakes, crackers or the like, means for depositing in sequence single units of said series onto said lower cake, cracker or the like, said means including a reciprocable frame having opposed escapement members carried by opposite sides of said frame and each effective

alternately to support said series and spaced vertically by substantially the thickness of a single unit, and means to reciprocate said frame.

In testimony whereof, I have signed my name to this specification.

EDWARD E. LAWRENCE.
